UNITED STATES PATENT OFFICE

ISAAC CLINTON NICHOLSON, OF PROVIDENCE, RHODE ISLAND.

DESIGN FOR AN EMBLEM, BUTTON, RING, PIN, OR ARTICLE OF SIMILAR NATURE.

53,251.

Specification for Design.

Patented Apr. 29, 1919.

Application filed February 5, 1919. Serial No. 275,258. Term of patent 7 years.

To all whom it may concern:

Be it known that I, ISAAC CLINTON NICHOLSON, a citizen of the United States, residing at Providence, in the county of Providence and State of Rhode Island, have invented a new, original, and ornamental Design for Emblems, Buttons, Rings, Pins, or Articles of Similar Nature, of which the following is a specification, reference being had to the accompanying drawing, forming part thereof.

The figure in the drawing is a face view of an emblem illustrating my new design.

The figure in the drawing is lined, in the world panel for red, and in the veteran panel for blue.

I claim:

The ornamental design for an emblem, button, ring, pin, or article of similar nature, as shown.

ISAAC CLINTON NICHOLSON.
